UNITED STATES PATENT OFFICE.

JOHN PHELAN, OF PITTSBURG, PENNSYLVANIA, ASSIGNOR OF ONE-HALF TO
RANKIN C. NEBINGER, OF SAME PLACE.

RAIL-JOINT.

SPECIFICATION forming part of Letters Patent No. 512,392, dated January 9, 1894.

Application filed September 20, 1893. Serial No. 485,995. (No model.)

To all whom it may concern:

Be it known that I, JOHN PHELAN, a citizen of the United States, residing at Pittsburg, in the county of Allegheny and State of Pennsylvania, have invented certain new and useful Improvements in Rail-Joints; and I do declare the following to be a full, clear, and exact description of the invention, such as will enable others skilled in the art to which it applies to make and use the same, reference being had to the accompanying drawings, and to the letters of reference marked thereon, which form a part of this specification.

My invention relates to an improvement in that class of rail joints wherein fish plates are employed to hold the contiguous ends together, and it consists of certain improvements in the construction of such joints whereby the plates are made to grip or bind against the rails more securely and thereby effect a better joint; and it also consists of an improvement in devices for holding the nuts of the plate bolts, which devices are especially adapted to my improved construction and by which the release of the nuts unintentionally is rendered impossible.

Referring to the accompanying drawings for a detailed description of my invention: Figure 1 represents a side elevation of a complete arrangement; Fig. 2, a cross section on the line $x-x$, of Fig. 1; Fig. 3, a cross section on the line $y-y$, of Fig. 1; Fig. 4, a detail view in perspective of the wedge for holding the nuts.

The reference letter a indicates the contiguous rail ends which rails may be of any preferred form, although I have here shown them as the style usually employed in street railways. Arranged on opposite sides of these rails are the fish plates b and c , the former b , being of the usual form, while the plate c , is provided, in addition to the usual flanges d , with the vertical ribs e . These ribs are arranged in pairs and extend from the outer side of the plate to a point beyond the edges of the flanges d , and the space occurring between each pair is cast with a raised portion therein, thus elevating the plane of the plate at this point. Between each pair of ribs e and in the raised portion between them is formed a bolt hole f , through which the bolt

g is adapted to extend, its head being arranged on the outer side of the plate b . Fitted on the end of the bolt g , adjacent to the plate c , is the usual nut h , which is adapted to be 55 screwed down between the ribs e , and to rest loosely on the raised portion between them.

i indicates a wedge which consists of a substantially fork-shaped device tapering to a small thickness at its lower end and having 60 two arms or prongs k , and joined by a body portion l . Surrounding the body of the wedge and extending parallel with the arms k down to their lower ends is a flange m which forms as it extends along the arms an elongated recess or passage of a size capable of receiving and holding snugly the nuts h of the bolts g , while the space or passage between the arms k is of such a size that it will snugly hold the bolt. This wedge is shown in use in Figs. 1, 65 2, 3, and 4, of the drawings and there it is passed one between each pair of the ribs e and resting upon the raised portion between the ribs, with the nut h fitting snugly between the parts of the flange m , and the bolt received by the passage between the arms k . 70 As this wedge is driven down the nut is consequently forced out and the plates drawn more tightly together. Formed integral with the plate c , and just below each pair of ribs 75 e , is a stationary wedge n , which is arranged so that its smaller end will be received between the arms k of the wedge i , when the latter wedge is placed in position and as said wedge is driven home the ends of the arms k 80 will be forced over the gradually diverging sides o , of the wedge n , and thereby cause them to spread and to bind firmly and immovably on said sides. To facilitate this operation the arms k are constructed of spring 85 metal and are given a very strong resistance so that when driven down by the help of a hammer or other driving tool they will bind against their respective sides with force sufficient to overcome all tendency to be displaced accidentally. Thus it will be obvious 90 that by this construction a combined nut lock and device for tightening the fish plates is provided, for, owing to the incapability of the wedge i from turning between the ribs e , 95 the nut cannot be displaced without removing the wedge i , and owing to the tension 100

caused by the wedge *i*, the plates are drawn tightly together and the bolts *g* assisted in their operation.

Formed on the lower flanges of the plates *b* and *c* are the grippers *p*, which extend downwardly therefrom to a point below the base flanges of the rails *a*, and thence inwardly for a distance equal to about that of the vertical portion of the grippers. These grippers are 10 adapted to co-operate with the base plate *q*, which is located under the base flange of the rail and has its lower face formed with two laterally inclined portions *r*, one on each side, and extending nearly to the longitudinal center of the plate. These inclined portions are 15 adapted to be engaged by the inwardly extending arms of the grippers *p*, so that when the plates *b* and *c* are tightened, by the means before described, the grippers will be drawn 20 inwardly with the plates *b* and *c* and cause the base plate *q* to be forced up against the base flange of the rail *a*, by reason of the grippers acting on the inclined portions *r* of such 25 base plate. By this construction it will be obvious that a much more secure joint is produced than ordinarily and that the parts when properly arranged will be as rigid as possible under any circumstances.

Having thus described my invention, what 30 I claim as new, and desire to secure by Letters Patent, is—

1. A rail joint comprising a pair of fish plates arranged one on each side of the contiguous ends of the rails, a bolt passing

through the rails and plates, a stationary 35 wedge formed integral with one of the plates and adjacent to the bolt, and a fork-shaped removable wedge adapted to pass below and on each side of the nut or bolt head and to have the ends of its arms pass on either side 40 of the stationary wedge and thereby lock itself and the nut in place and assist the bolt in its function of binding the plates, substantially as described.

2. A rail joint comprising a pair of fish 45 plates arranged on either side of the contiguous ends of the rails, a bolt passing through the plates and rail and provided with a nut, a pair of ribs formed on the fish plate upon which the nut rests and on each side of the 50 nut, a stationary wedge formed on the plate having the ribs and directly under the nut, and a removable forked wedge adapted to pass between the ribs and under and on each side of the nut and to have the lower ends of 55 its arms pass one on either side of the stationary wedge and thereby lock the wedge in place, and prevent the nut from being displaced and assist the bolts in their function of binding the plates, substantially as described.

In testimony whereof I affix my signature in presence of two witnesses.

JOHN PHELAN.
